UNITED STATES PATENT OFFICE

113,501

DESIGN FOR A CORNER LIGHTING FIXTURE OR SIMILAR ARTICLE

Henry G. Alm, Elkhart, Ind., and Sterling B. McDonald, Chicago, Ill., assignors to The Adlake Company, a corporation of Illinois

Application April 25, 1938, Serial No. 76,734

Term of patent 14 years

To all whom it may concern:

Be it known that we, Henry G. Alm and Sterling B. McDonald, citizens of the United States of America and residents of Elkhart, county of Elkhart and State of Indiana, and Chicago, county of Cook and State of Illinois, respectively, have invented a new, original, and ornamental Design for a Corner Lighting Fixture or Similar Article, of which the following is a specification, reference being had to the accompanying drawing, forming a part thereof, wherein

Fig. 1 is a perspective view of a corner lighting fixture, showing my design;

Fig. 2 is a top plan view;

Fig. 3 is a side elevational view of the fixture looking in a direction parallel to one of the walls upon which the fixture is mounted;

Fig. 4 is a bottom plan view; and

Fig. 5 is a front elevational view looking in the direction of the arrow 5 in Fig. 2.

We claim:

The ornamental design for a corner lighting fixture or similar article, substantially as shown.

HENRY G. ALM.
STERLING B. McDONALD.
